[57] ABSTRACT

A device for locking sliding patio doors and the like employing an over-center spring-induced toggle action imparted to a lock bolt to selectively urge the lock bolt into locked position or hold it in an unlocked position. The spring functions as a keeper for retaining the bolt in the locked position and as a stop for determining the unlocked position of the bolt. A pedal member impinging on the spring releases the lock by forcing the spring to shift the bolt from locked to unlocked position.

FOOT OPERATED PATIO DOOR LOCK

BACKGROUND OF THE INVENTION

Many locks are known in the prior art for locking a sliding patio door, or the like, in closed position. Typically such a lock includes a bracket secured to the door frame sill and arranged to mount a bolt manipulable between positions of locked engagement with, and unlocked disengagement from an aperture in the sliding door which is registerable with the bolt when the door is in the closed position. Conventional locks of this type have been relatively complex in construction, and the bolts thereof cumbersome to manipulate between locked and unlocked position. Typically the bolt is slidably and/or rotatably mounted in a sleeve portion of the mounting bracket and spring biased toward an extended position of locked engagement with the door aperture. Often these locks are situated in corners where the exercise of the manual dexterity required to operate them is further inhibited by the awkward position one must assume to reach them.

SUMMARY OF THE INVENTION

The present invention relates to an improved lock for sliding patio doors or other sliding sashes which is simple in construction and very easily manipulable between locked and unlocked position.

A lock in accordance with the present invention comprises a bracket or equivalent mounting element adapted for securance to the sill of a sliding patio door, or the like, a lock bolt carried by the mounting element translatable towards or away from the door between an extended locked position of engagement with an aperture in the door and a retracted unlocked position of disengagement from the aperture, and overcenter spring means secured between the mounting element and the bolt for imparting a toggle action to the bolt. The bolt is moved to the unlocked position by a pedal cover impinging on the spring means, forcing the spring to drive the bolt to the unlocked position, with the spring means acting as a stop. The spring also functions as a keeper to maintain the bolt in both the locked and unlocked position. With this simple construction the bolt is easily actuated by either foot or hand pressure to the unlocked position by depressing the pedal and to the locked position by urging the bolt toward the aperture in the door.

THE DRAWING

FIG. 1 is a broken perspective view of a sliding patio door embodying a lock in accordance with the present invention;

FIG. 2 is a top view of the present invention;

FIG. 3 is an end elevation sectional view of the lock of the present invention in the locked position, and cooperating portions of the sliding door;

FIG. 4 is an end elevation sectional view of the lock of the present invention in the unlocked position;

FIG. 5 is an end elevation view of the lock of the present invention; and

FIG. 6 is a rear elevation of the present invention.

DESCRIPTION OF THE PREFERRED EMBODIMENT

A sliding glass door 10 shown in FIG. 1 includes a door 11 having a pane of glass 12 or the like framed within a sash 13 mounted for slidable translation longi-

tudinally along a track 14 in a conventional manner. In order that the door may be locked in its closed position wherein the sash is in end abutment with the jamb 16 of the frame, there is provided a lock 17 in accordance with the present invention which is preferably mounted on the sill of the door adjacent the jamb in an unobtrusive manner. The lock 17 consists of a bracket 20 secured to the sill through mounting holes 21, a cover 22 vertically slidably affixed to the bracket, and a locking bolt 25 laterally slidable through the bracket 20, as shown in FIGS. 2 and 5. The bolt has a head 24 which limits translation in the locked direction.

The interior construction of the present invention, shown in FIG. 3, includes an overcenter spring means 30 secured at one end to the notch 31 in the bolt 25, and at the other end to the bracket 20. The spring end in the notch acts as a stop for determining the retracted position of the bolt. The spring 30 is preferably a band spring of omega (Ω) configuration, functioning as a keeper for resiliently retaining the bolt in its extended or retracted position with its toggle action. Secured to the inside top of the cover 22 is a short screw 32 received through the hole 33 in the bracket, with the head 34 of the screw acting as a stop to determine the limit of upward vertical travel of the cover.

In the locked position as shown in FIG. 3, the bolt is received in the aperture 36 of the sash 13, preventing any sliding translation of the sash. To open the door 11 the bolt is retracted from the locked position by applying either hand or foot pressure downward on the cover 22, forcing the cover to slide down on the bracket 20, the sides of the cover acting as a guide on the bracket. The head 34 of the screw carried by the cover impinges on the curved portion of the spring 30, compressing it and forcing it through the center position until the end of the spring in the notch 31 springs out, drawing the bolt out of the aperture 36. The bolt continues to travel laterally until stopped by the spring contacting the bracket 20, as shown in FIGS. 4 and 6. The bolt is free of the aperture, and the door can be opened at will.

It should be noted that the neutral center position of the omega spring is reached as the linear portions of the spring 30 are substantially normal to the bolt 25. When the spring is moved beyond the neutral position in either direction, the spring force exerted on the bolt is in the same direction, urging the bolt onward. Therefore locking the closed door 11 is accomplished by applying lateral pressure, usually by foot or hand, to the bolt, urging it to engage the aperture 36. The curved section of the spring compresses as it approaches the center position while it also forces the screw head vertically upward, lifting the cover. As the spring passes through the neutral position it expands, exerting force to drive the bolt into the aperture, securing the door.

Thus the preferred extremely simple construction of the present invention provides a lock which is easily actuated to locked or unlocked position with either foot or hand pressure, allowing for ready operation in hard-to-reach locations. It should be noted that the lock may be mounted on the translatable portion of a sliding sash assembly registerable with an aperture in the stationary portion of the assembly. Further, the lock and associated aperture may be situated at any convenient point along the sliding sash, according to the requirements of the installation. The lock may also be used to maintain the sliding door or sash immobile in an open or partially open condition.

I claim:

1. A lock for two members linearly translatable with respect to each other to secure said two members immobily together, said lock comprising a mounting element adapted for securance to the first of said two members, a lock bolt mounted upon said element for translation transversely of the second of said two members between an extended locked position of engagement with an aperture in said second member and a retracted unlocked position of disengagement therefrom, overcenter spring means secured between said mounting element and said lock bolt selectively effective to urge said lock bolt to said locked position, or to said unlocked position, and cover means mounted upon said mounting means for slidable translation between an extended position and a retracted position of impingement upon said spring means to force said spring means to urge said lock bolt to said unlocked position.

2. The lock according to claim 1 wherein said mounting element comprises a bracket including a pair of parallel spaced walls extending right angularly from an interconnecting bracket web.

3. The lock according to claim 2 wherein said spaced walls have aligned apertures slidably transversed by said bolt.

4. The lock according to claim 3 wherein said cover

means includes parallel spaced sides perpendicular to said spaced walls and extending right-angularly from and interconnecting top web.

5. The lock according to claim 4 wherein said spring means comprises an omega-shaped band spring including a U-shaped central portion with aligned oppositely directed lineal portions extending from its opposite ends.

10 6. The lock according to claim 5 wherein the first of said lineal portions is end secured to said bracket web and the second of said linear portions being end secured to said lock bolt.

15 7. The lock of claim 6 wherein said second linear portion is engageable with one of said bracket walls to determine said unlocked position of said lock bolt.

20 8. The lock according to claim 5 wherein said cover means further includes rod means depending from said top web and received through an opening in said bracket web, said rod means suitably aligned for impingement upon said U-shaped portion of said spring.

25 9. The lock according to claim 7 wherein said lock bolt has an enlarged head at one end engageable with said first of said walls in said locked position of said bolt and spaced apart therefrom in said unlocked position.
